UNITED STATES PATENT OFFICE.

ALBION K. NIXON, OF SAN FRANCISCO, CALIFORNIA, ASSIGNOR OF ONE-HALF TO
ALBERT CASPER, OF VALLEJO, CALIFORNIA.

CASTER.

Application filed July 27, 1921. Serial No. 487,935.

To all whom it may concern:

Be it known that I, ALBION K. NIXON, a citizen of the United States, residing in the city and county of San Francisco and 5 State of California, have invented new and useful Improvements in Casters, of which the following is a specification.

This invention relates to a caster, and especially to a caster of the compound roller 10 type.

One of the objects of the present invention is to generally improve and simplify casters such as are used in conjunction with heavy furniture, pianos or the like, and especially 15 to provide a caster in which rolling friction is greatly reduced, marring of the floor surface, etc., prevented, and in which jarring of the article supported and resistance to override an obstruction when encountered is 20 reduced to a minimum.

Further objects will hereinafter appear.

The invention consists of the parts and the construction, combination and arrangement of parts as hereinafter more fully described and claimed, having reference to the 25 accompanying drawings, in which—

Fig. 1 is a side elevation of one form of the caster.

Fig. 2 is a cross section of the same.

Fig. 3 is a perspective view of the roller guard.

Fig. 4 is a side elevation of another form of the caster.

Fig. 5 is a cross section of the same.

Referring to the drawings in detail, and particularly to Fig. 1, A indicates the shank of a caster, 2 the upper head, 3 the lower head, and 4 the bearing arms of the caster. The heads 2 and 3 are secured with relation 35

40 to each other in the usual manner as indicated at 5, and a ball bearing race 6 is interposed between the head members to permit a free swivel action between the same. The arms 4 of the caster are interposed as shown 45 in Fig. 2, and connecting the lower ends of the arms is a bearing pin 7, upon which is journaled a roller 8. This roller is disposed within a second roller generally indicated at 9 which will hereinafter be termed the track 50

55 ring. This ring is formed of sheet metal or any suitable material, and is considerably larger in diameter than the roller 8. Formed on the inner side of the ring is an annular rib or ridge 10, and formed in the center portion of the roller 8 is a groove 11, which

permits the roller 8 to straddle the rib 10, thus permitting the rib to form a track for the roller 8 which secures said roller against lateral movement with relation to the track member.

By referring to Figs. 1 and 2, it will be seen that the diameter of the roller 8 is so small when comparison is made with the interior diameter of the track member 9, that unless means were provided for maintaining the roller 8 in constant engagement with the inner side of the track member, displacement of the ring or roller 8 might take place. To avoid such displacement, a guard generally indicated at 12, has been 60 provided. This guard consists of a pair of arms 14, the lower ends of which are perforated as at 15 to permit the pin 7 to pass therethrough. The upper ends of the arms 14 are connected by a cross-piece 16, and 65 this piece is bent or grooved as at 17 to straddle the rib or track 10. The guard thus formed maintains the roller in constant engagement with the inner surface of the track member and the rib 10, and thus prevents 70 displacement of the roller with relation to the track member or vice versa.

In the other form of the invention illustrated in Figs. 4 and 5, a track ring 18 is employed. The inner surface of the ring is 85 concaved as at 19 to form a track for a roller 20. The exterior surface of this roller is convex to conform with the inner formation of the track ring. The caster in general, illustrated in Figs. 4 and 5, is also provided 90 with a pair of connected swivel heads 21 and 22 and the bearing lugs shown at 23 support the bearing pin 24, upon which the roller 20 is journaled.

For the purpose of securing the roller 95 against lateral movement, and also for the purpose of maintaining it in engagement with the inner track surface 19, a pair of side plates 25 and 26 have been provided. These side plates enter annular recesses 27 and 28 formed in the respective sides of the track ring, and they are freely turnable in these recesses and they are also freely turnable upon the pin 24.

To prevent unnecessary friction between 105 the track ring and the side plates 25 and 26, and between the end surfaces of the roller 20, the pin 24 is shouldered as at 30. This shouldering of the pin maintains a predetermined spacing between the roller 20 and the 110

plates 25 and 26, and similarly between the track ring and the plates, thus reducing friction to a minimum. The roller 20 will, at all times, be maintained in engagement 5 with the inner track surface and lateral movement of the track ring with relation to the roller, or vice versa, will be prevented. In other words the plates 25 and 26 perform the same function as the guard 12 and the 10 annular rib or track member 10.

There are three main objects sought in the present invention: First, to minimize rolling friction; second, to prevent marring of surfaces rolled over or upon, and third, to 15 prevent jarring of the article supported and resistance to override an obstruction when encountered.

The first object is obtained by providing the compound rollers indicated at 8 and 9. 20 The rolling friction takes place between the outer surface of the small roller and the inner surface of the track ring. The inner surface of said track ring, where depressions would have a tendency to exist, is composed 25 of material of a harder substance than the planes which sustain the outer ring when in motion. The depressions which would be caused on the surface of the material rolled upon, when a load is applied to the roller, 30 will be minimized. The inner surface of the track ring being curved gives more of a bearing surface to the small roller than would be given if the roller came in direct contact with a plane surface, such as a wooden floor, thereby decreasing depression and 35 minimizing friction.

The second object is obtained by applying soft rubber, or other suitable material, to the outer portion of the track ring as indicated at 40. This surface comes in contact with the hard wood floor when in motion; the rubber forming a cushion between the roller, the track ring and the floor. Actual rolling wear and tear take place on the 45 inside surface of the track ring, that is the ring acts as a track only when the roller is in motion. The soft rubber on the outer surface of the track ring gives a large bearing support when a load is applied, and it 50 does not hinder the rolling effect of the track ring.

The third object is obtained by employing the track ring. When it approaches an obstruction, for instance, such as indicated 55 at 41, the track ring remains stationary and forms an inclined track for the roller 8 between the points indicated at 42 and 43. The roller 8 rolls within the track ring while this remains stationary, that is the 60 roller 8 moves from the point 43 to the point 42 and when it passes the high point of the obstruction, which is indicated at 42, it is obvious that the track ring will follow and that the track ring and the roller will 65 come centered with relation to each other

when a plane or even surface is again reached.

This action of the two rollers one with relation to the other is important as it not only lessens the jar to the article supported, 70 but it materially reduces the amount of power or force required to override an obstruction.

While certain features of the present invention are more or less specifically illustrated, I wish it understood that various changes in form and proportion may be resorted to within the scope of the appended claims, similarly that the materials and finish of the several parts employed may be 80 such as the experience and judgment of the manufacturer may dictate or varying uses may demand.

Having thus described my invention, what I claim and desire to secure by Letters Patent is—

1. In a device of the character described, a compound roller support comprising a circular track member, and a roller adapted to travel on the inner surface of the track member, one of said members having a groove 90 therein and the other of said members being formed to operate in said groove.

2. In a device of the character described, a compound roller support comprising a circular track member, and a roller adapted to travel on the inner surface of the track member, one of said members having a groove 95 therein and the other of said members being members being formed to operate in said groove, 100 and a guard device arranged between the track member and the roller members to maintain said members in cooperative relation.

3. A device of the character described 105 comprising a swivel head, a pair of bearing arms carried by the head, a bearing pin disposed between the arms, a roller journaled thereon, a track ring exterior of the roller having an inner track surface for the reception of the roller and an exterior track surface for engagement with the surface rolled upon, and means having loose connections with said bearing pin for securing the roller 110 against lateral movement with relation to 115 the track ring.

4. A device of the character described comprising a swivel head, a pair of bearing arms carried by the head, a bearing pin disposed between the arms, a roller journaled thereon, a track ring exterior of the roller having an inner track surface for the reception of the roller and an exterior track surface for engagement with the surface rolled upon, and a guard member pivotally supported by the bearing pin and engageable with the track ring to maintain the roller in constant engagement therewith.

5. A device of the character described 120 comprising a swivel head, a pair of bearing 125

- arms carried by the head, a bearing pin disposed between the arms, a roller journaled thereon, a track ring exterior of the roller having an inner track surface for the reception of the roller and an exterior track surface for engagement with the surface rolled upon, an annular rib formed on the inner track surface and centrally thereof, an annular central groove in the roller permitting the roller to straddle the rib, and a bail-shaped guard pivotally mounted on the bearing pin, the upper end of said guard being recessed to straddle the annular track rib.
- 5 6. In a device of the character described a swivel head, a pair of bearing arms carried thereby, a bearing pin supported by the arms, a roller journaled thereon, a track ring surrounding the roller and having a track surface on its inner side for the reception of the roller, and an exterior track surface for engagement with a surface to be rolled upon, an annular recess formed in
- 10 each side of the track ring, and a circular plate forming a closure for each side of the track ring, and adapted to be received by said recesses, said plates being eccentrically journaled upon the bearing pin.
- 15 7. In a device of the character described a swivel head, a pair of bearing arms carried thereby, a bearing pin supported by the arms, a roller journaled thereon, a track ring surrounding the roller and having a track surface on its inner side for the reception of the roller, and an exterior track surface for engagement with a surface to be rolled upon, an annular recess formed in
- 20 each side of the track ring, a circular plate forming a closure for each side of the track ring and adapted to be received by said recesses, said plates being eccentrically journaled upon the bearing pin, and means for maintaining said plates out of frictional engagement with the roller and the track ring.

ALBION K. NIXON.
